UNITED STATES PATENT OFFICE.

EDWARD COLEMAN, OF NEW YORK, N. Y.

LOOSE-LEAF BINDER.

No. 801,969.

Specification of Letters Patent.

Patented Oct. 17, 1905.

Application filed November 18, 1904. Serial No. 233,296.

To all whom it may concern:

Be it known that I, EDWARD COLEMAN, a citizen of the United States, and a resident of New York, in the county of New York and State of New York, have invented certain new and useful Improvements in Loose-Leaf Binders, of which the following is a specification.

My invention relates to a loose-leaf binder or ledger; and the invention consists mainly in such construction of the binder that by direct and positively acting parts, which can be cheaply made and easily put together, the binding-flanges which confine the leaves may be easily closed and separated by the use of a key, thus producing a cheap, compact, powerful, and durable binder and one which will not get out of order as to the proper parallelism of the binding-flanges or otherwise.

My invention also consists in such construction of the parts of the binder that a narrow-backed binder may be expanded from a narrow to a very wide space between the binding-flanges, thus increasing the capacity of the binder and furnishing when expanded an ample space for the convenient manipulation of the leaves.

The invention also consists in the construction, arrangement, and combinations of the parts, all as hereinafter described and claimed.

In the accompanying drawings, to which reference is made, Figure 1 is a plan view of a loose-leaf binder made in accordance with my invention. Fig. 2 is an end elevation of the same. Fig. 3 is an enlarged plan view of the back, showing the parts in extended position. Fig. 4 is a sectional elevation on line 4-4 of Fig. 3. Figs. 5 and 6 are transverse sectional views on lines 5-5 and 6-6 of Figs. 1 and 3, respectively. Fig. 7 is a plan view of the operating bar or plate, and Fig. 8 is a plan view of the main back.

In the drawings, 2 2 designate the covers, 3 the main back, and 4 4 the sides or binding-flanges, which are provided with filing pins or posts 5, preferably telescoping posts, which are adapted to hold sheets of paper to be applied to them in the usual way.

The back 3 is by preference made of metal in concaved or other appropriate shape to form the upturned edges 7 7, so as to receive the six bridge-pieces 8, 9, 10, 12, 13, and 14 or any other proper number, according to the size of the binder. The ends of the back 3 are by preference finished with the plates 55 15 and 16, having the overlying end flanges

17 18 to conceal the parts beneath. The side pieces or binding-flanges 4 4 are held to the back by right-angled supports 19 20, preferably in the form of practically continuous plates and by rivets or screws hereinafter described, which pass through slots into the bridge-pieces, and said supports are by preference made integral with the said side pieces or flanges. Each end of each side piece or binding-flange is by preference finished with an inwardly-turned flange 21, and these are concealed by the end plates 15 16 and their flanges 17 18.

The support 19 is formed with two slots 22 23 and is held to the back 3 and its bridges 9 10 and 12 by screws or similar devices 24 25, and the support 20 is formed with two like slots 26 27 and is held to the back and its bridge-pieces 10 and 12 by screws or similar devices 28 29. The slots 26 27 are offset from the slots 22 23, as shown clearly in Figs. 1 and 3, and the meeting edges of the bottom plates or supports 19 20 are of increased width adjacent to the slots, allowing the slots to be of increased length, thus increasing the distance of spread of the binder and allowing long posts 5 to be used, making the binder of large capacity when extended and small in size when closed. The edge of the support 20 opposite those portions of the support 19 which contain the slots 22 and 23 is cut away or recessed, as shown at 30 31, to receive the extended edge or portion of the support 19, and the support 19 opposite those portions of the support 20 which contain the slots 26 and 27 is cut away or recessed, as shown at 32 33, to receive the extended edge or portion of the support 20.

34 designates a longitudinally-movable bar or plate located beneath the supports 19 20. (See Fig. 7.) It is operated by a threaded operating-shaft 35, located beneath it—that is, between the main back 3 and the said bar or plate 34. The bar or plate 34 takes its bearings, as here shown, in the center of the main back on recesses 36, 36^a, 36^b, and 36^c, formed on the upper edges of the bridge-pieces 9 10 12 13, which are alternately offset from each other, as shown in Fig. 8, and is held down in said recesses permanently by the supports 19 20, and it is connected to the operating-shaft 35 by a block 37, secured to its under surface, which slides on the back 3 and operates between the bridge-pieces 12 13, which latter serve as abutments for the shaft, the shaft being adapted to be rotated by a 110

crank or key 38 in bearings 39 40, formed in the bridge-pieces 12 13, as clearly shown in Fig. 4.

To the bridge-piece 9 is centrally fulcrumed on a pin 41, Figs. 3 and 8, a triangular or bell-crank lever 42, formed with slots 43 44 at its ends. The slot 44 engages with a stud or pin 45 on the top of the operating bar or plate 34, while the slot 43 engages with a stud or pin 46 on the under surface of the support 19. Another bell-crank lever 47 is fulcrumed on a stud or pin 48 on the bridge-piece 12 and like the lever 42 is formed with slots 49 50 at its ends, the slot 50 being connected to a stud 51 on the top of the operating bar or plate 34, (see Figs. 3 and 8,) while the slot 49 is connected to a pin 52 on the under side of the support 19, so that when the operating bar or plate 34 is moved back and forth by the operating-shaft 35 one of the side pieces or binding-flanges 4 and the support 19, to which it is connected, will be moved out or in laterally.

The above-described construction and operation is duplicated for the support 20 and its binding-flange 4—that is to say, on the bridge-piece 10 is centrally fulcrumed on a stud or pin 53 a bell-crank lever 54. One end of this lever is connected to the top of the operating-bar 34 by a pin and slot 55 56, while its opposite end is connected to the under side of the support 20 by a pin and slot 57 58. On the bridge-piece 13 is centrally fulcrumed on a pin or stud 59 a bell-crank lever 60, one end of which is connected to the top of the bar or plate 34 by a pin and slot 61 62, while its opposite end is connected to the support 20 by a pin and slot 62 63. The pins or studs 41 and 48 are held by the bridge-pieces on one side of the center of the binder, while the pins or studs 53 and 59 are held by the bridge-pieces on the opposite side of the center of the binder, and the bar or plate 34 is recessed at the edges, as shown at 64, 65, 66, and 67 in Fig. 7, thus forming the opposite edge extensions 68, 69, 70, and 71 for the pins or studs 45, 55, 51, and 61, as shown clearly in said figure.

The covers 2 2 are each bound to a hinge-piece 72 (see Figs. 5 and 6) of wood or metal and are fastened to the outside of the side pieces or binding-flanges 4 4 by screws 73 73, as clearly shown in Fig. 4.

While the ends of the bell-crank levers might be connected to the bar or plate 34 and to the supports 19 and 20 by other means, I prefer the slot-and-pin connections, for in operation the pins have a free cam-like action on the edges of the slots, closing the sides of the binder with sufficient force and without overstrain upon the operating-shaft 35, and the action is uniform on both sides and at both ends of the binder, and by locating the bell-crank levers on top of the bar or plate 34 and below the supports 19 and 20 the levers are held in proper alinement and out of contact with the paper placed upon the filing

pins or posts 5, for when the binder is contracted the supports 19 and 20 close over the bell-crank levers and over the operating bar or plate 34 and over the operating-shaft.

What I claim as new, and desire to secure by Letters Patent, is—

1. In a loose-leaf binder a longitudinally-movable bar, a back adapted to receive said bar, a binding-flange connected to the back, another binding-flange, a support therefor held by the back, one or more levers fulcrumed to the back and connected at one end to said support and at the other end to the said bar, and means for moving the bar back and forth, substantially as described. 80

2. In a loose-leaf binder a longitudinally-movable bar, a back adapted to receive said bar, opposite binding-flanges, supports therefor held by the back and one or more levers each fulcrumed to the back and connected at one end to said bar and at the other end to said supports, substantially as described. 85

3. In a loose-leaf binder a pair of levers fulcrumed at one side of the center of the back, another pair of levers fulcrumed at the opposite side of the center of the back, a longitudinally-movable bar operating between said fulcrums and to which the levers are connected at one end and supports to which the opposite ends of the levers are connected, 95 substantially as described.

4. In a loose-leaf binder, a back, a longitudinally-movable bar, a pair of bell-crank levers fulcrumed to said back, a sliding support connected to said levers and provided with a binding-flange, another pair of bell-crank levers fulcrumed to said back, another support connected to said last-mentioned levers and provided with a binding-flange, and means for connecting each of said bell-crank levers to 100 the said bar, substantially as described. 105

5. In a loose-leaf binder, a back, bridge-pieces secured in said back, a longitudinally-movable bar held on said bridge-pieces, bell-crank levers fulcrumed on fixed bearings and connected at one end to said bar and connected at the other to supports which slide over the bell-crank levers, substantially as described. 110

6. In a loose-leaf binder, a back, bridge-pieces secured in said back, a shaft journaled in the bridge-pieces, a bar held on the bridge-pieces above said shaft and connected to the shaft, bell-crank levers fulcrumed on fixed bearings and connected at one end to said bar and connected at the other end to supports which slide over the bar, the said supports being provided with binding-flanges, substantially as described. 115 120

7. In a loose-leaf binder, a back, a longitudinally-movable bar held in said back, bell-crank levers fulcrumed on fixed bearings and connected at one end to said bar, a binding-flange support formed with slots and held on the back by pins in said slots and means for connecting said support to the outer ends of 125 130

said bell-crank levers, substantially as described.

8. In a loose-leaf binder, a back, a pair of binding-flange supports portions of whose inner edges close beyond the center of the back, slots in said extended portions and pins therein for holding the supports to the back, a longitudinally-sliding bar and bell-crank levers connected to said bar and to said supports and fulcrumed on fixed bearings substantially as described.

9. In a loose-leaf binder a longitudinally-movable bar, a pair of pivots on said bar at each side of its longitudinal center, a pair of levers fulcrumed on fixed bearings at each side of said bar and connected to said pivots, movable supports connected with said levers and binding-flanges carried by said supports, substantially as described.

10. In a loose-leaf binder a longitudinally-movable bar, a pair of pivots on said bar at each side of the longitudinal center thereof, a pair of fixed studs at each side of said bar, combined with bell-crank levers fulcrumed on said studs, and formed with slots at the ends to connect with the said pivots, and with slots at the opposite ends, supports connected with said bell-crank levers in the last-mentioned slots and binding-flanges connected with said supports, substantially as described.

11. In a loose-leaf binder a longitudinally-

movable bar, a pair of pivots on said bar at each side of the longitudinal center thereof, a pair of fixed studs at each side of said bar in line with the pivots on the bar, combined 35 with bell-crank levers fulcrumed on said studs, and formed with slots at the ends to connect with the said pivots and with slots at the opposite ends and supports for the binding-flanges, having pins to connect with the last- 40 mentioned slots, substantially as described.

12. In a loose-leaf binder a back, a shaft held in bearings on said back, a bar connected to said shaft, and bell-crank levers having fixed fulcrums held by said back, pivots for 45 said levers on said bar, supports connected to the outer ends of said levers and flanges held by said supports, substantially as described.

13. In a loose-leaf binder, a back, opposite slotted supports provided with binding-flanges 50 having filing-pins, a bar located below the said supports, two pairs of bell-crank levers located between the said supports and the said bar and fulcrumed on fixed bearings and connected to the bar and supports and a threaded 55 shaft connected to the said bar and held in bearings beneath said bar, substantially as described.

EDWARD COLEMAN.
